UNITED STATES PATENT OFFICE.

JAY C. SMITH, OF MARION, INDIANA, ASSIGNOR TO AMERICAN SIGN COMPANY, OF KALAMAZOO, MICHIGAN, A CORPORATION.

SIGN.

965,544.

Specification of Letters Patent. Patented July 26, 1910.

Application filed February 10, 1908. Serial No. 415,107.

To all whom it may concern:

Be it known that I, JAY C. SMITH, a citizen of the United States, and a resident of Marion, in the county of Grant and State 5 of Indiana, have made certain new and useful Improvements in Signs, of which the following is a specification.

This invention relates to improvements in signs.

10 The object of this invention is to provide in a sign in which the sign characters are formed by lenses, an improved means for securing the lenses in position in a sheet metal sign face.

15 Further objects, and objects relating to details of construction, will definitely appear from the detailed description to follow.

I accomplish the objects of my invention by the devices and means described in the 20 following specification.

The invention is clearly defined and pointed out in the claim.

A structure embodying the features of my 25 invention is clearly illustrated in the accompanying drawing, forming a part of this specification, in which:

Figure 1 is a detail front elevation of a 30 structure embodying the features of my invention. Fig. 2 is a transverse section thereof, taken on a line corresponding to line 2—2 of Fig. 1. Fig. 3 is an enlarged detail showing the arrangement of one of the lenses in the lens or face plate of the sign. Fig. 35 4 is a detail perspective of the lens plate showing one of the lens openings. Fig. 5 is a detail horizontal section, taken on a line corresponding to line 5—5 of Fig. 2.

In the drawings, similar reference numerals refer to similar parts throughout the 40 several views.

Referring to the drawing, I provide a casing 1 preferably consisting of frame pieces 14, on which the side walls of the casing are secured. These side walls are preferably 45 formed of sheet metal, as illustrated, thin sheet steel being preferred. The front or face wall 2 of the casing is provided with a plurality of openings 3, which are grouped to form the characters or follow the outline 50 of the characters or symbols of the sign.

The face plate or wall 2 also has slits, as 4, extending from the openings, preferably from the lowest points of the openings. The edges of these slits are bent or deflected in

opposite directions to form spring thread 55 engaging members 5 and 6. A plurality of lenses are provided, each having or comprising a head 8, the outer surface of which is preferably convex, the inner surface 10 being flat. From this flat surface projects 60 a threaded shank 9. The inner end of the threaded portion is preferably concave, as shown at 11 in Fig. 3. These lenses are screwed into the openings 3 tightly so that the inner flat face or shoulder 10 bears 65 against the outer face of the face plate or wall 2, putting stress or tension on the thread engaging members 5 and 6 for locking the lenses in place, and also as the lenses are thus screwed home, the openings 3 are 70 sealed thus preventing the entrance of moisture into the casing, which is particularly injurious where electric lamps are used as a lighting means, it being a common requirement of electric inspection in most cities 75 that signs using electric lamps must be moisture proof. This I secure in a very simple and effective manner.

The illuminating means preferably consists of a plurality of electric incandescent 80 lamps, the sockets 13 of which are secured to the top and bottom rear frame pieces 14, the bulbs 12 being arranged in the sockets in the usual, or any desired manner. These lamps are arranged outside of the outer 85 lenses of the sign characters, so that the light is evenly distributed within the casing and to all the lenses,—that is, none of the lamps are located directly at the rear of the lenses in alignment therewith, but are without the line of the outer lenses so that the light passing through the lenses is largely reflected light and evenly distributed. By this arrangement, should one or more of the lamps become extinguished, the general appearance 90 of the sign is not materially affected, because no particular character of the sign depends upon a particular lamp for its illumination, the lenses being illuminated by illuminating the entire interior of the 100 casing, and, as stated, from points outside of the line of outer lenses.

The lamps can be connected by any suitable system of wiring, as 15, which is here shown in conventional form only.

In practice, the walls of the casing are preferably of suitable reflecting material, or coated therewith, to secure the best results

from the lamps and to effectively reflect the light through the lenses. By mounting the lenses in the thin sheet metal front wall, as described, they are secured without the necessity of separate fastenings and with a minimum of obstruction to the passage of light through the lenses.

In use, each of the lenses has the appearance of an electric light and a comparatively small number of lamps secures this result, thus not only saving in the cost of production, but also in running expense,—that is, the current consumed and lamp expense,—and, as previously stated, should a portion of the lamps be extinguished, the appearance of the sign is not seriously affected. It is obvious that the lenses might be colored, as desired. If desired, the face plate 2 of the sign can be made detachable so that the sign may be changed by provid-

ing a new face plate with the desired characters formed thereon by means of the lenses.

Having thus described my invention, what I claim as new and desire to secure by Letters Patent is:

A sign comprising a face plate of sheet metal containing a circular opening, having a slit at one side thereof, and a lens provided with a shoulder arranged to contact with said plate and a shank having a complete screw-thread, the thread being adapted to enter said slit and engage the edges of said opening throughout the circumference thereof, the thread and shoulder coacting to put stress on the metal to practically close the slit and seal the lens in place.

JAY C. SMITH.
